T. E. CROUCH.
RIM NIGHT LATCH.
APPLICATION FILED FEB. 24, 1920.

1,350,299.

Patented Aug. 24, 1920.

UNITED STATES PATENT OFFICE.

THOMAS E. CROUCH, OF STAMFORD, CONNECTICUT, ASSIGNOR TO THE YALE & TOWNE MANUFACTURING COMPANY, OF STAMFORD, CONNECTICUT.

RIM NIGHT-LATCH.

1,350,299.

Specification of Letters Patent. Patented Aug. 24, 1920.

Application filed February 24, 1920. Serial No. 361,025.

To all whom it may concern:

Be it known that I, THOMAS E. CROUCH, a citizen of the United States, and a resident of Stamford, in the county of Fairfield and State of Connecticut, have invented certain new and useful Improvements in Rim Night-Latches; and I do hereby declare the following to be a full, clear, and exact description of the invention, such as will enable others skilled in the art to which it appertains to make and use the same.

My invention relates to an improvement in night latches, the object being to provide improved means for securing the bolt mechanism to the door independently of the casing so that the operation of the bolt may be visibly tested before assembling the casing or cover, and it consists in a spider secured to the door and carrying the bolt mechanism and a casing detachably secured to the spider.

It further consists in the details of construction as will be more fully explained and pointed out in the claims.

In the accompanying drawings; Figure 1 is a view in elevation of the latch and its keeper; Fig. 2 is a view in section through the casing, between the wrought metal plate and the outer face of the casing to which the said plate is attached, and also through the keeper; Fig. 3 is a view in elevation of the casing from the open side thereof; Fig. 4 is a view in elevation of the spider attached to the door and carrying the bolt mechanism; Fig. 5 is a view in longitudinal transverse section of the latch and its keeper; Fig. 6 is a view in perspective of the keeper and Fig. 7 is a view in front elevation of the casing.

10 represents the spider secured by screws 11 to the door 12 and provided at one end with the flange 13 slotted for the passage of the bolt 14 which latter is projected by a spring and is retracted by a roll back 15 on the knob shank 16, in the usual and well known manner. The bolt may of course be retracted by a mechanism 15^a actuated by a key from the outside of the door, in the usual and well known manner.

15 The spider 10 is also provided at its side near its rear end with the integral flanges 17, each of which is provided with an out-

wardly turned tongue 18 as shown in Figs. 4 and 5.

The casing 19 which is an integral structure punched and drawn from a metal blank, comprises an outer face plate and integral ends and sides, one end having an opening corresponding in size and position with the opening in flange 13 of the spider 10 for the passage of the bolt 14. Secured within the casing 19 and against the inner surface of the casing is the wrought metal plate 20 having lugs 21^a which enter recesses in the sides and ends of the casing for permanently securing it to the latter. This plate, which carries the bolt stopping device, as shown in Fig. 3, is provided at its opposite sides with the integral right angled hook shaped lugs 21 which are adapted to engage the outwardly turned tongues 18 on the side flange 17 of the spider 10 for locking the casing to the spider and consequently to the door.

In assembling the parts, the spider or frame with the bolt assembled therein is secured to the door and its operation visibly tested before applying the casing. The latter is passed over the projecting end of the bolt and then moved endwise rearwardly until the front end of the casing is in contact with the end flange 13 of the spider, this rearward endwise movement carrying the hook shaped lugs 21 on the wrought metal plate 20 under the outwardly turned tongues 18 on the spider. After the parts have been thus assembled and secured, the casing is further secured to the spider, by the screws 22 passing through the outer end of the casing and engaging screw threaded holes 23 in the end flange 13 of the spider thus positively locking the casing to the spider. To remove the casing the door should be opened so as to expose the head of the screw 22 and the latter removed. The casing is then moved endwise forwardly so as to disengage the lugs 21 from the tongues 18 and then by retracting the latch bolt it can be lifted off the spider.

The bolt may be retracted by the knob at 100 the inner side of the door, and by key mechanism 15^a in the usual manner from the outer side.

The knob 24 is provided with a shank 16

which passes through the outer face of the casing and through the wrought metal plate 20 and its end is upset or spun over the cam or roll back 15 and thus operates to permanently secure the plate 20 to the casing 19. The outside sheet 25 of the strike plate or keeper is also drawn from a single blank and is provided at the inner face of its front or strike plate with a steel reinforcing or wear plate 26. The plate 26 extends throughout the length of the front face of the strike plate as shown in Figs. 5 and 6, and it and the strike plate are provided with screw holes for the passage of screws for securing it to the jamb and with a hole 28 for a rivet 32 which permanently secures the parts together. The strike plate or keeper is further secured to the jamb by the screw 29 which passes through the plate 30 which rests at one edge on the steel reinforce 26 and is provided at its opposite edge with one or more tongues 31 which rest in recesses or slots in the outside shell of the strike plate or keeper. When the parts of the latter are assembled as shown and secured by rivet 32, the plate 30 is permanently secured within the strike plate so that the latter can be handled as a unit.

It is evident that many slight changes might be resorted to in the relative arrangement of parts shown and described without departing from the spirit and scope of my invention. Hence I would have it understood that I do not wish to confine myself to the exact construction and arrangement of parts shown and described but,

Having fully described my invention what I claim as new and desire to secure by Letters-Patent, is:—

1. The combination of a spider adapted to be secured to a door, a bolt and its mechanism mounted in and carried by the spider, and a casing detachably secured to the spider.

2. The combination of a spider adapted to be secured to a door, a bolt and its mechanism carried by the spider, a casing, the casing and spider having interlocking engaging means and bolt actuating means carried by the casing.

3. The combination of a spider adapted to be secured to a door, a bolt and its mechanism carried by the spider, a casing, the casing and spider having interlocking engaging means whereby the casing is secured in place and removed by an endwise move-

ment, and securing means passing through one end of the casing and through a member of the spider for locking the casing against endwise movement.

4. The combination of a spider adapted to be secured to a door and provided with side flanges and an end flange, a bolt and its mechanism carried by said spider, a casing having securing means interlocking with lugs on the side flanges of the spider, securing means connecting an end of the casing and the end flange on the spider and bolt actuating mechanism carried by the casing.

5. The combination of a spider adapted to be secured to a door, a bolt and its mechanism carried by the spider, a casing, a plate secured against the inner face of the casing and having means for interlocking with the spider, and means on the casing for actuating the bolt.

6. The combination of a spider adapted to be secured to a door, a bolt and its mechanism carried by the spider, a casing, a plate secured against the inner face of the casing and having means for interlocking with the spider, and a knob on the casing for actuating the bolt, the knob spindle passing through the casing and plate and upset at its inner end against the inner face plate and locking the latter to the casing.

7. The combination of a spider adapted to be secured to a door and having side flanges, a bolt and its mechanism carried by the spider, a casing, a plate secured against the inner face of the casing, the said plate and side flanges of the spider having interlocking engaging means, and a knob carried by the casing for actuating the bolt.

8. The combination of a spider adapted to be secured to a door and having side flanges and an end flange, a casing, a plate secured to the casing and against the inner surface of the outer face of the latter, the said plate and spider having interlocking securing means, means passing through one end of the casing and the end flange of the spider for locking the two parts together, a bolt and mechanism carried by the spider and means for actuating the bolt.

In testimony whereof I have signed this specification in the presence of two subscribing witnesses.

THOMAS E. CROUCH.
